UNITED STATES PATENT OFFICE.

THOMAS F. DONHAM, OF TERRE HAUTE, INDIANA.

CHAINLESS CORN-PLANTER.

1,031,538.

Specification of Letters Patent.

Patented July 2, 1912.

Application filed October 26, 1911. Serial No. 656,919.

To all whom it may concern:

Be it known that I, THOMAS F. DONHAM, citizen of the United States, residing at Terre Haute, in the county of Vigo and State of Indiana, have invented certain new and useful Improvements in Chainless Corn-Planters; and I do declare the following to be a full, clear, and exact description of the invention, such as will enable others skilled in the art to which it appertains to make and use the same.

This invention relates to seeders and planters and more especially to those usually employed for dropping corn; and the object of the same is to produce a machine of this character having a marking device rotating in contact with the ground and producing a mark thereon opposite each hill planted, the marker having a cam for actuating the seed-dropping mechanism just at the proper time. This and other objects are accomplished by the construction hereinafter more fully described and claimed, and as shown in the drawings wherein—

Figure 1 is a side elevation and Fig. 2 a plan view of this device in its preferred form; Fig. 3 is a side elevation and Fig. 4 a plan view showing a slight modification thereof; Fig. 5 is a perspective detail on an enlarged scale showing the construction of the V-shaped marker.

The corn-planter features of this device comprise, in the present instance, a tongue T connected to a frame F carrying two shoes S or furrow openers S upon each of which is mounted a grain box B from which the corn or seed is passed down the drill or dropping-tube at intervals by the seed-dropping mechanism which forms no part of the present invention save as it is controlled by the marker wheel to be described below. In rear of each shoe is here shown a planting or covering wheel W, and the seed-dropping mechanism is here illustrated as controlled by a rock shaft R extending from one shoe to the other. The general nature of the construction and operation of this much of the mechanism is so well understood that I will not go further into details.

Coming now more particularly to the present invention, in its preferred form I mount a marking wheel 1 on an axle 2 between the two shoes S and so disposed that some considerable weight will fall upon this wheel and cause it to rotate by its contact with the ground. On its periphery at

one point is secured a marker, preferably consisting of a wrought iron angular core 4 to which by screws 5 or otherwise is detachably connected a steel facing 6 of V-shaped cross section and so disposed that the angle of the V stands radial to the wheel and parallel with its axis and constitutes the marker itself; while the wings or sides of the V, as at 7, may form cams for a purpose to appear below, but individual and separate cams 8 will preferably be secured to the sides of the wheel 1 at other points than opposite said marker. The latter disposition of said cam is necessary where the axle 2 extends between the two shoes S and the wheel 1 is disposed between them, but the wings 7 of the marker itself may constitute cams as more clearly shown in Fig. 3 where the wheel is mounted on hangers 9 depending from the tongue T and is disposed some distance forward of the seed-planting mechanism. The former construction is perhaps preferable, because the entire machine is more compact; but the latter construction may often be desired where this invention is adapted to a corn planter already constructed. In either construction of the machine, the use of screws 5 securing the steel facing 6 to the core 4 is of advantage because when the surface of the facing is worn by contact with the ground or with the trigger or both, the screws can be removed and the entire facing reversed as will be clear.

The connection between the marker wheel and the seed-dropping mechanism consists, in my preferred construction, of one or more triggers 15 secured upon and depending from the rock shaft R in position to be struck by the cams 8 as the marker wheel 1 rotates; and in the construction of my invention where the marker wheel is disposed forward of the shoes the trigger 16 is pivoted at 17 to the tongue or other suitable support and a link 18 connects the remote end of the trigger with a rod 19 projecting from the rock shaft, and in this case the side of the marker itself constitutes the cam which strikes the lower end 15' of the trigger 16 as the marker wheel rotates. In connection with this device I employ a guide bar 20 pivoted as at 21 to the tongue T or at some central point on the framework so that it can be thrown outward to either side of the machine, and from the outer ends thereof hangs a pendant indicator consisting of a plumb line 23 having a weight 24 at

its lower extremity for a purpose to appear below.

In use, as the corn planter is driven along the ground the marker wheel rotates upon it and presses out a rather wide and flat path which can be plainly seen by the driver when he comes around the field the second time. At each revolution of the wheel the sharp edge of its marker enters the ground 5 and makes a line across said path. If the wheel is disposed between the two shoes, the cams 8 must be so located on the wheel that they will strike the triggers 15 and oscillate the rock shaft R at just the proper 10 moment to drop the seed through the shoes when the mouths of the seed-dropping tubes therein reach a point in line with the mark just made. On the other hand, if the marker wheel is disposed forward of the 15 shoes, the separate cams 8 may be dispensed with and the wings 7 of the marker itself employed, that wing or face which is uppermost striking the lower end of the trigger 16 just a proper time to cause it, through its 20 connections with the rock shaft, to turn the latter and drop the seed through the tubes in the shoes at points opposite the mark that has just been made. In either event the marker wheel continues its rotation as 25 the machine is driven forward, and this operation is repeated across the field. When the driver comes alongside a row that has just been planted, or makes his next trip 30 around the field alongside such a row, the guide bar and indicator are so disposed that the weight will travel over the path made by the marker wheel on the previous trip. If the machine is planting correctly, just 35 as the indicator points to or passes over a mark previously made, the cam should oscillate the rock shaft as above described and 40

seed will be dropped in line with the mark being made on this trip. In this manner the operator can cross-check the field being planted. It is my intention that the marker wheel shall be so finely hung on its axis and the marker itself shall be so heavy that when it is lifted free of the ground the marker will descend to the bottom of the wheel in order to give the operator a chance to set the 45 machine to operate a little earlier or a little later and thus correct any inaccuracies which might occur by reason of obstructions encountered in a rough field. The proportions and details of parts may be safely left 50 to the manufacturer. 55

What is claimed as new is:

In a corn planter, the combination with the framework, the seed dropping mechanism including two boxes with their drills, 60 a rock shaft connecting said boxes, and a rod projecting radially from said shaft; of a wheel journaled in a support carried by the framework and having a flat periphery 65 adapted to travel on the ground between said boxes, a radially projecting marker and cam extending from the periphery and standing parallel with the axis of the wheel, a trigger pivoted between its ends in the framework and having one end adapted to 70 be struck by said cam, and a link connecting its other end with the rod projecting from the rock shaft, all as and for the purpose set forth.

In testimony whereof I have hereunto set 75 my hand in presence of two subscribing witnesses.

THOMAS F. DONHAM.
